(57) **CLAIM**

We claim the ornamental design for a combination spoon and fork, substantially as shown and described.

DESCRIPTION

FIG. 1 is a front perspective view of a combination spoon and fork in accordance with the present design.

FIG. 2 is a back perspective view of the combination spoon and fork.

FIG. 3 is a top plan view of the combination spoon and fork.

FIG. 4 is a bottom plan view of the combination spoon and fork.

FIG. 5 is a right side elevational view of the combination spoon and fork.

FIG. 6 is a left side elevational view of the combination spoon and fork.

FIG. 7 is an enlarged upper end elevational view of the combination spoon and fork; and,

FIG. 8 is an enlarged lower end elevational view of the combination spoon and fork.
